UNITED STATES PATENT OFFICE.

ARCHIE M. BAIRD, OF TOPEKA, KANSAS, ASSIGNOR OF ONE-HALF TO HENRY W. JACOBS, OF TOPEKA, KANSAS.

BOILER.

1,115,156.

Specification of Letters Patent. Patented Oct. 27, 1914.

Application filed August 18, 1913. Serial No. 785,241.

To all whom it may concern:

Be it known that I, ARCHIE M. BAIRD, a citizen of the United States, and resident of Topeka, in the county of Shawnee and State 5 of Kansas, have invented certain new and useful Improvements in Boilers, of which the following is a description, reference being had to the accompanying drawings, which form a part of my specification.

10 My invention relates to the fire-box of a boiler, pertaining more especially to the door-sheet and flue-sheet of a fire-box of the locomotive type.

15 The object of my invention is to provide a fire-box having a door-sheet and flue-sheet so constructed and arranged that the desired flexibility will be obtained to compensate for expansion and contraction which occur in the fire-box, and thus relieve the flues 20 and other parts of the boiler of undue strains and stresses, thereby avoiding cracking and leaking in the various parts of the fire-box encountered with fire-boxes as heretofore constructed.

25 My invention possesses other advantages inherent in the construction, which will be apparent from the following detailed description of the accompanying drawings, wherein:

30 Figure 1 is a perspective view of my improved door-sheet. Fig. 2 is a perspective view of my improved flue-sheet. Fig. 3 is a perspective view of a modified form of door-sheet constructed in accordance with my invention. Fig. 4 is a perspective view of a 35 modified form of flue-sheet embodying my invention. Fig. 5 is a longitudinal sectional view of a sectional type of locomotive fire-box,—a portion of the fire-box being broken 40 away,—showing the application of my improved fire door-sheet and flue-sheet illustrated in Figs. 1 and 2. Fig. 6 is a similar view of a modified or dog-leg throat type of locomotive boiler, illustrating the application 45 of the modified form of door-sheet and flue-sheet shown in Figs. 3 and 4.

As an exemplification of my invention, I have shown the same applied to what is known as the Jacobs-Shupert type of sectional fire-box, to which my invention is 50 more especially adapted, as clearly illustrated

in Fig. 5, wherein the fire-box is composed of a sufficient number of channel sections 8, substantially U-shape in cross-section; the various sections 8 being secured together 55 with intervening stay-sheets 9. The fire-box end of the boiler in Fig. 5 is also shown provided with an outer sectional shell composed of members 10, which are formed with the flanges extending outward from 60 the convexed side of the sections; the concaved side of these outer sections 10 being presented inwardly toward the fire-box; and these sections 10 are secured together with the stay-sheets 9, intervening, thus supporting 65 the fire-box in place. The lower ends of the fire-box sections 8, as well as the outer sections 10, are securely riveted to the mud-ring 11, as clearly shown in Fig. 5. It is evident that this construction of fire-box 70 permits of considerable expansion and contraction because of the fact that the amount of metal in the respective sections, in a transverse direction is greater than the actual 75 distance between the flanges of each section when in normal condition. Difficulties, however, have been encountered in the construction of the door and flue sheets, which, heretofore, were made of flat sheet metal, secured not only to the adjacent fire-box 80 sections, but also to the outer sections of the boiler, in a similar manner to the stay-sheets. Such constructions of door-sheet and flue-sheet do not provide the necessary 85 flexibility, but subject the flues and other parts of the fire-box and boiler to undue strains.

To overcome the difficulties heretofore encountered, I provide a dished door-sheet and a flue-sheet 12 and 13, respectively, as more 90 clearly shown in Figs. 1 and 2. The sheets are dished so as to produce the angularly extending portions 12^a and 13^a, respectively, the free edges whereof are off-set or bent substantially at right angles to the portions 12^a and 13^a so as to provide the flanges 12^b and 13^b, respectively. The door-sheet 12 is, of course, also provided with the flanged opening 14, the flanges 15 telescoping with the flange 16 of the outer shell section 17, the flanges 15 and 16 being riveted together in 100 the usual manner. The flanges 12^b and 13^b

of the door-sheet 12 and flue-sheet 13, extend substantially entirely about the three sides of the sheets; the flanges, however, being cut away at the lower corners of the sheets, 5 as shown at 12^c and 13^c, respectively, see Figs. 1 and 2, where the door-sheet and flue-sheet are secured to the mud-ring. The flue-sheet 13 is also provided with the requisite number and size of flue holes 18 into 10 which the ends of the flues 19 are welded, rolled or expanded.

In Figs. 3 and 4, I show modified forms of door-sheet and flue-sheet, adapting my invention to a different type of locomotive 15 boiler. The door-sheet 20 is dished so as to provide an angularly extending portion 20^a of increasing width toward the bottom of the sheet as clearly shown in Fig. 3, to permit the door-sheet to slope forwardly toward the top; the edge of the portion 20^a being bent so as to provide an attaching flange 20^b adapted to extend parallel with the flange of the adjacent fire-box section 8^a as clearly shown in Fig. 6. The lower 20 corners 20^c of the portion 20^a are not flanged or bent so as to permit the lower ends to be secured to the mud-ring 11^a as very clearly shown in Fig. 6. The door-sheet 20, like 25 door-sheet 12, is also provided with the opening 14^a, surrounded by the flange 15^a which is preferably formed integral with the sheet, see Fig. 3. The flue-sheet 21, illustrated in Fig. 4, is slightly bent rearwardly as clearly shown at 22, in order to accommodate it to the modified form of fire-box 30 illustrated in Fig. 6. The flanges of the respective sheets are shown provided with perforations in order to permit the sheets being riveted to the flanges of the adjacent fire-box sections and intervening stay-sheets. As shown in the drawings, both door-sheet 35 and flue-sheet are of a size corresponding with that of the adjacent fire-box sections to which they are secured, and do not extend 40 upward through the water space of the boiler to the outside boiler shell or sections.

By dishing or concaving the door-sheet and flue-sheet, so as to provide a greater amount of metal than the actual distance between the attaching edges of the adjacent fire-box sections and mud-ring, and having the door-sheet and flue-sheet independent of the outer boiler-shell or sections, it is evident that they will permit the necessary expansion and contraction of the fire-box sections and relieve the flues and other parts of the boiler of undue strains and stresses. 45

In off-setting the edges of the door-sheet and flue-sheet to produce the attaching flanges, the sheets are provided with a series of curves, substantially Z-shape in cross-section, whereby the sheets are given the desired flexibility necessary to meet the expansion and contraction encountered in loco-

motive fire-boxes of the kind shown and described. 50

I have shown what I believe to be the best forms of my improved door-sheet and flue-sheet whereby the life of the fire-box and the flues will be extended; a flexible door-sheet and flexible flue-sheet independent of the outer boiler sections or shell; but the same may be varied in certain respects without, however, departing from the spirit of my invention, and I do not wish to be understood, therefore, as limiting myself to the exact construction shown and described. 55

What I claim is:—

1. A boiler provided with a sectional fire-box, the door-sheet and flue-sheet whereof are secured to the adjacent sections of the fire-box and independent of the outer boiler-shell, said sheets being composed of sheet metal formed so as to provide off-set flanges extending substantially parallel with the main or body portions thereof whereby the sheets are secured to the flanges of the fire-box sections so as to permit expansion and contraction in the fire-box without transmitting the stresses to adjacent portions of the boiler and to the flues of the boiler. 80

2. In a boiler provided with a sectional fire-box, a flue-sheet secured independently of the outer boiler-shell, composed of sheet metal having three edges thereof off-set so as to provide flanges extending substantially parallel to the main or body portion thereof and to the flanges of the fire-box section to which the flanges are adapted to be secured so as to permit expansion and contraction in the fire-box without transmitting the stresses to the flues of the boiler. 95

3. In a boiler provided with a sectional fire-box, a door-sheet secured independently of the outer boiler-shell, formed of sheet metal with three edges thereof off-set so as to provide flanges extending substantially parallel to the main or body portion thereof and to the flanges of the fire-box section to which the flanges are adapted to be secured so as to permit expansion and contraction in the fire-box without transmitting the stresses to the adjacent portions of the boiler. 105

4. In a boiler of the class described provided with a fire-box composed of channel sections having flanges extending outwardly, the flue and door-sheets whereof are formed so as to provide substantially right angularly extending portions about three edges thereof, with the one or outer portion extending substantially parallel with and beyond the plane of the main or body portion of the sheets and parallel with the flanges of the adjacent fire-box sections to which the sheets are secured, while the other or intermediate portion extends substantially at right angles to the main or body portions of the sheets and is adapted at the lower edges 110

115

120

125

thereof to overlap and be secured to the mud-ring of the boiler.

5. In a boiler of the class described, provided with a sectional fire-box, a door-sheet having its top and side edges off-set so as to provide portions extending substantially parallel with the main portion of the sheet,

with the intermediate part of the off-set portion increasing in width toward the bottom of the sheet.
